UNITED STATES PATENT OFFICE.

JOHN A. BEMISH, OF ROCHESTER, NEW YORK.

VACUUM-TRAP.

1,013,730.

Specification of Letters Patent.

Patented Jan. 2, 1912.

Application filed July 3, 1911. Serial No. 636,810.

To all whom it may concern:

Be it known that I, JOHN A. BEMISH, a citizen of the United States, and resident of Rochester, in the county of Monroe and 5 State of New York, have invented certain new and useful Improvements in Vacuum-Traps, of which the following is a specification.

This invention relates particularly to automatic devices for controlling the escape of water of condensation from steam-heating systems of the vacuum type although it is applicable to other devices of similar character.

15 In devices of the kind in question it has heretofore been proposed to employ a cup-shaped member moving in a chamber provided with an inlet and an outlet, said member being slidingly guided upon a hollow 20 stem, or guide, projecting upwardly from the outlet of the chamber. This cup is provided at the bottom with a valve-member coöperating with an escape-vent for water 25 in or upon the guide or stem. As the water of condensation collects in the chamber it causes the cup to float, whereby the valve-member is held in position to close the water-vent. When the water rises high 30 enough in the chamber, however, it overflows the upper edge of the cup until the buoyancy of the cup is sufficiently reduced to cause it to fall. The downward movement of the cup not only opens the water-vent, but also causes a further quantity of 35 water to flow into the cup, so that a considerable amount of water is discharged through the water-vent. As soon as the water has been sufficiently discharged from the cup, it regains its buoyancy and rises, 40 thus closing the water-vent.

In devices of the kind just described, as previously proposed, valve-members having a sliding engagement with their seats have been employed, and such devices have been 45 unsatisfactory not only because liable to more or less leakage, but also because the construction in question necessitates such close fitting of the moving parts that they are liable to become clogged, so that the device 50 may fail to operate properly.

One object of the present invention is to avoid the use of sliding-surfaces in the valve-members, and to this end I employ an arrangement of concentric valve seats 55 hereinafter described.

Another object of the invention is to pro-

vide a vacuum-trap of the type in question with a simple form and arrangement of air-vent and controlling-valve therefor, and to this end I locate the air-vent at the top of 60 the guide-member upon which the float-cup is mounted, and employ an air-valve extending upwardly through the top of the float-chamber, as hereinafter described.

In the accompanying drawings:—Figure 65 1 is a vertical, median section of a vacuum-trap embodying the present invention; Fig. 2 is a horizontal section on the line 2—2 in Fig. 1; and Fig. 3 is a section on a larger scale on the line A—A in Fig. 2. 70

The illustrated embodiment of the invention has the usual float-chamber 3, provided with an inlet 4, which may be connected with the outlet-end of a radiator or system of radiators, and an outlet 5 which is connected with the drainage-system by which the water of condensation is carried away. A check-valve 6 is shown as controlling the inlet 4, although this is not essential to the invention. 75

The float is in the form of a cup 7 of thin sheet-metal vertically movable in the float-chamber and open at the top. The float-cup is provided at the bottom with a collar 8, which is shown as secured within an opening in the cup, although it may be formed integrally therewith, if preferable. This collar has an easy sliding fit upon a hollow cylindrical stem 9, which is screwed into the outlet-opening at the bottom of the float-chamber. The stem thus constitutes a guide for the collar 8, and serves to hold the cup in upright position and restrict it to vertical movements. The upper end of the stem 9 is covered by a cap 11, which is formed integral with the stem, being connected therewith, at intervals, by radial arms 12, as shown particularly in Fig. 2. The cap is of greater diameter than the stem and depends around the upper extremity of the 90 stem, while the top of the cap is spaced above the upper extremity of the stem. The cap and the stem thus form between them an annular space or passage constituting a vent for water of condensation, this vent 95 communicating, through the hollow stem, with the outlet-opening 5. At the inside of the water-vent the stem 9 is provided, at its upper extremity, with an annular inclined valve-seat 10, while the cap is provided, at 100 its lower edge, with an oppositely-disposed concentric annular valve-seat 13. The upper

105

110

extremity of the collar 8 is also provided with concentric annular inclined surfaces, which conform to the valve-seats 10 and 11, so that the collar is adapted to operate as 5 a valve-member, acting, when in uppermost position, to close the water-vent against the escape of water, air or steam.

In Fig. 1 the float-cup is shown as in its normal position, being buoyantly sustained 10 by water in the float-chamber, so that the water-vent is closed by the valve-member 8. It will be noted that in this position of the parts both the cup and the water-vent are effectually sealed against the discharge 15 of water, for the escape of water from the cup is prevented by the engagement of the valve-seat 13 with the corresponding surface on the valve-member 8, while the leakage of water into the cup or the water-vent 20 between the valve-member 8 and the stem 9 is prevented by the engagement of the valve-seat 10 with the corresponding valve-surface. Accordingly the stem may be formed with a loose fit in the valve-member 25 8, so that the danger of these parts binding is eliminated, while at the same time the valve acts effectually to hold the water-vent closed.

To permit the escape of small quantities of 30 air which may accumulate in the radiators, a small air-vent is provided in the middle of the cap 10, this vent being controlled by a needle-valve 14. The needle-valve is threaded in the top of the float-chamber, and it 35 passes through a gland 15 to the exterior of the chamber, so that it may be accessible for the purpose of adjustment. This arrangement permits a slight leakage through the trap sufficient to carry away the air, 40 without permitting the escape of any substantial amount of vapor.

I claim:—

1. A vacuum-trap having, in combination, a float-chamber provided with an inlet and an outlet, a hollow stem projecting 45 upwardly from the outlet and provided with a valve-seat, a cap covering the upper end of said stem and provided with a valve-seat concentric with the valve-seat on the stem, the two valve-seats being spaced apart to 50 provide a water-vent between the cap and the stem, and a float-cup provided at the bottom with a valve-member slidably mounted on, and guided by said stem, said member having two valve-surfaces coöperating respectively and simultaneously with said valve-seats when the float-cup is in raised position, whereby the water-vent is normally sealed against the flow of fluid 55 both from within and from without the cup.

2. A vacuum-trap having, in combination, a float-chamber provided with an inlet and an outlet, a hollow fixed guide projecting upwardly from the outlet and provided at the top with an air-vent, and, at a lower point, with a water-vent, a float-cup 65 slidably mounted on said hollow guide and provided with a valve-member normally closing the water-vent, and a valve-rod of 70 which the lower end extends downwardly to and coöperates directly with the air-vent, said valve-rod being adjustably supported in vertical position and passing upwardly through the float-cup and the top of the 75 float-chamber so as to be adjustable from the outside of the vacuum-trap.

JOHN A. BEMISH.
